REVERSE CURRENT RELAY SYSTEM

Labeeb B. Haddad, New Haven, Conn., assignor
to The Safety Car Heating and Lighting Com-
pany, Inc., a corporation of Delaware

Application December 28, 1946, Serial No. 718,989

5 Claims. (Cl. 320—33)

1

This invention relates to electrical power systems and, more in particular, to a reverse current relay of the type used in the electrical systems of railway cars.

An object of this invention is to provide an electrical system of the type used on railway cars which is extremely efficient and dependable in operation. A further object is to provide a relay switch for use on railway cars which will connect the generator to the battery system at all times when such a connection is desirable. A further object is to provide a relay switch of the above character which is light in weight, sturdy in construction, dependable in operation, and in all ways satisfactory for use under widely varying conditions. These and other objects will be in part obvious and in part pointed out below.

The invention accordingly consists in the features of construction, combinations of elements, arrangements of parts and in the several steps and relation and order of each of the same to one or more or the others, all as will be illustratively described herein, and the scope of the application of which will be indicated in the following claims.

In the drawings:

Figure 1 is a partial schematic view of one embodiment of the invention;

Figure 2 is a vertical section of the relay switch of Figure 1;

Figure 3 is a top plan view of the switch of Figures 1 and 2; and,

Figure 4 is a sectional view on the line 4—4 of Figure 2.

In the illustrative embodiment of the present invention the electrical system for a railway car is provided with a relay switch which is extremely dependable and efficient in use. Referring now to Figure 1 of the drawings, the storage battery system for a railway car is represented at 2 and an axle-driven generator is represented at 4. The electrical load connected across the storage battery is represented at 6 and, for the sake of simplicity, the switching and voltage control mechanisms at the load are omitted. As will be explained more fully below, the generator is connected to the battery only when the voltage of the generator is greater than that of the battery; and this connection is provided by a reverse current relay switch 8. Relay switch 8 is represented somewhat schematically in Figure 1 but is shown in detail in Figures 2, 3 and 4. Referring to the upper portion of Figure 2, relay switch 8 is provided with a switch 12 having a fixed contact 14 and a movable contact 16. Contact 14 is mounted on a spring arm 16, the right-hand end of which is fixed to a mounting block 18 by a pair of screws 19 (see also Figures 3 and 4).

2

The end of arm 16 is electrically insulated from block 18 by flat rectangular insulators 21 above and below the arm and by insulating bushings (not shown) surrounding screws 19. The electrical circuit from contact 14 is through arm 16 and thence through a wire attached to the right-hand end of the arm (see Figure 1).

Block 18 is rockably mounted on a pair of pivots 23 on the opposite sides of the block and 10 mounted respectively in a pair of brackets (see Figure 4) which are integral and form a U-member, extend freely through the brackets and are threaded into holes in the opposite sides of the block, thus to provide a low-friction mounting 15 for the block. Threaded through block 18 is a horizontal lever rod 25 (see Figure 2) which carries at its left-hand end a connecting rod 24, there being a coupling provided by a pin 26 threaded in lever rod 25 and having its ends projecting through slots 27 in rod 24. The lower end of rod 24 is threaded into the top of an armature 28 which is generally cylindrical but has slightly tapered ends as will be discussed below. Armature 28 is adapted to move up and down 25 a limited distance to open and close switch 10; when the armature is in its lower position switch 10 is opened, and when in its raised position, switch 10 is closed. This movement of the armature is facilitated by a counterweight 29 which 30 is threaded onto the right-hand end of lever rod 25; and counterbalances the weight of the armature and the movement is performed by a magnetic assembly which surrounds the armature.

35 This magnetic assembly is formed by a magnetic shell 30 and two sets of coils nested therein and forming therewith respectively an upper magnetic circuit and a lower magnetic circuit. Shell 30 has an upper end ring 32; a middle ring 40 34 and a lower end ring 36; and these rings are mounted in fixed parallel relationship on a pair of channel members 38 and 40 (see also Figure 3) positioned at opposite sides of the rings. Each ring is held to each of the channel members by 45 three screws 42 and the rings and channel members are of magnetic steel so as to provide, as indicated above, an upper magnetic circuit formed by rings 32 and 34 and the upper ends of the channel members, and a lower magnetic circuit formed by rings 34 and 36 and the lower ends of the channel members.

55 The rings have concentric axial openings in which is fixed a thin walled brass tube 44, the internal diameter of which is such as to permit armature 28 to slide easily up and down within the tube. Mounted on the top of ring 32 is a top bearing disc 46 which is of brass and which carries a stainless steel bearing sleeve 48 through

which rod 24 extends. Bearing disc 46 is held in place by a plurality of screws 50 threaded into ring 32. Similarly, at the bottom a bearing disc 52 is clamped to the bottom ring 36 by screws 54, and threaded through the plate is a bearing pin 56. The cylindrical upper end of pin 56 projects into an axial recess 58 in the bottom end of armature 28.

As pointed out above, rod 24 is threaded into the upper end of armature 28 and the armature is moved up and down to close and open switch 10. During this movement, the armature is guided by the combined action of tube 44 and bearing pin 56 on the armature and the action of rod 24 sliding in bearing sleeve 48. Brackets 22 are welded to the top of top ring 32, and at the left is a contactor bracket 60 upon which contact 12 is mounted by an arm 62 fixed to the bracket by a pair of screws 64 and insulated therefrom by rectangular flat insulators 66 and insulating bushings (not shown) around the screws.

The coil assembly for the upper magnetic circuit is formed by a voltage coil 68 which is hereafter referred to as the "lifting coil" and a series or current coil 70 hereafter referred to as the "upper series coil." The coil assembly for the lower magnetic circuit is formed by two voltage coils 72 and 74 hereafter referred to respectively as the "balancing coil" and the "holdout coil" and a "lower series coil" 76.

Referring again to Figure 1, the coils are connected in the electrical circuit in the manner indicated. The two series coils 70 and 76 are connected in series in the main generator current line with one side of coil 70 connected to generator 4 by a line 80 and with the other side of coil 76 connected through a line 82 to the contact 12 of switch 10. Contact 14 of the switch is connected through a line 84 to the positive side of the storage battery system. Thus, with switch 10 closed and with the generator voltage exceeding that of the storage battery system, a charging current flows through the circuit from the positive side of generator 4 through line 80, series coils 70 and 76, line 82, switch 10 and line 84 to the storage battery system.

Lifting coil 68 and balancing coil 72 also are connected in series, one side of the balancing coil being connected to the negative side of the generator by a line 86 and the other side of the lifting coil 68 being connected through a line 88 to contact 12 of switch 10. Contact 12 also is connected to the positive side of the generator through the low resistance circuit formed by line 82, series coils 76 and 70, and line 80. Therefore, lifting coil 68 and balancing coil 72 carry a current which varies directly with the voltage of the generator, and, as will be discussed below, this current flows through series coils 70 and 76.

Holdout coil 74 is connected at one side by a line 90 to the positive side of the generator and at the other side through a line 92 to the positive side of the battery. As pointed out above, the positive side of the battery system is connected to contact 14 of switch 10 and the positive side of the generator is connected through the low-resistance series coils 70 and 76 to contact 12 of the switch. Therefore, the holdout coil is connected directly across switch 10 so that when the switch is closed, this coil exerts no effect, whereas when the switch is open it carries a current which varies in direction and magnitude with the relative values of the voltages of the generator and the storage battery sys-

tem. Thus, when the voltage of the storage battery system exceeds that of the generator, switch 10 is normally open and a battery-discharging current flows through the holdout coil 74 and the generator, and, when the generator voltage exceeds that of the storage battery system, the direction of this current is reversed. At all times the magnitude of the current varies directly with the difference between these two potentials, so that when the voltage of the generator equals that of the storage battery system, there is no current flow through the holdout coil. When switch 10 is closed, there is no appreciable flow of current through the holdout coil because the resistance of series coils 70 and 76 is small, and therefore the voltage drop across these coils is small even when there is a heavy current flow therethrough.

The lifting coil 68 has approximately 1% more turns in it than does the balancing coil 72, and these two coils are arranged to exert opposing effects; that is, the lifting coil tends to move the armature up so as to close switch 10, whereas the balancing coil tends to move the armature down so as to open the switch. The same current flows through both coils so that the slightly larger number of turns in the lifting coil causes it to exert a corresponding greater force for any given current value. As indicated above, the upper series coil 70 is positioned in the magnetic circuit of the lifting coil, and the lower series coil 76 and holdout coil 74 are positioned in the magnetic circuit of the balancing coil 72.

The coils are so wound and connected that, when the generator voltage exceeds the battery voltage, the lifting coil 68 is assisted by its associated series coil 70, whereas the balancing coil is opposed or bucked by its associated series coil 76. However, when the voltage of the battery exceeds that of the generator, the effect of each of the series coils is reversed so that the lifting coil is opposed or bucked by its series coil, and the balancing coil is assisted by its series coil. Furthermore, when the voltage of the battery exceeds that of the generator, the holdout coil 74 assists the balancing coil, but when the generator voltage is above that of the battery, the holdout coil bucks the balancing coil.

As pointed out above, the lifting coil 68 and the balancing coil 72 are connected in series across the generator 4, and one side of this series circuit is connected to the juncture of the battery and the generator, whereas the other side of this series circuit is connected on the generator side of switch 10. Furthermore, the series coils 70 and 76 are connected in series between the generator and the switch, and therefore, current which flows from the generator through the lifting and balancing coils also flows through the two series coils.

With this arrangement, when the switch is open, a rise in the generator voltage causes current to flow in the lifting coil and the balancing coil, and this same current flowing through the two series coils produces additional effects which tend to close the switch; that is, the lifting coil is assisted by its series coil whereas the balancing coil is bucked by its series coil. As pointed out above, the lifting coil has 1% more turns than the balancing coil, and therefore the net effect resulting from the two coils working in opposition is a force tending to close the switch. This switch-closing force is small and is of the magnitude of 1% of the gross force of the lift-

ing coil which is the force which would be exerted by the lifting coil if it were not opposed by the balancing coil. However, the series coil associated with the lifting coil adds an additional force of approximately $\frac{1}{2}\%$ of the total force of the lifting coil and the balancing coil is weakened by its series coil to a similar extent. Thus, the two series coils produce an additional net force which is 1% of the force which would be exerted by the lifting coil if it were not opposed by the balancing coil. This effect of the series coils is added to this effect of the lifting coil to give a total switch-closing force equal to 2% of the gross force of the lifting coil.

As pointed out above, the holdout coil augments the effect of the balancing coil 72 as long as the voltage of the battery exceeds that of the generator, and, therefore, when the generator is stationary or operating at low speed, the holdout coil produces a substantial effect tending to hold the switch open. However, as the speed of the generator increases so that its voltage rises to that of the battery, the current flowing through the holdout coil diminishes towards zero. At any time that the voltage of the generator exceeds that of the battery, the direction of the current flow in the holdout coil is reversed so that this coil then bucks the balancing coil.

As indicated above, counterweight 29 is threaded onto lever rod 25 and therefore the counterbalancing effect of the counterweight is adjusted by turning it on the rod thereby moving it longitudinally of the rod. During use the counterweight is so adjusted and the other components of the assembly are of such magnitude that the switch closes substantially at the time the voltage of the generator exceeds that of the battery system.

When the switch is open and the voltage of the battery system exceeds that of the generator there is a substantial flow of current through holdout coil 74, the effect of which is additive to the effect of balancing coil 72. When the voltage of the generator is low and switch 10 is open there is no appreciable current flow through lifting coil 68 and balancing coil 72, and the effect of the holdout coil is very substantial and is sufficient to insure that the armature will not rise to close the switch.

The factors which are most important at the time of the closing of switch 10 have been referred to above but now will be reviewed briefly. Lifting coil 68 has approximately 1% more turns than does balancing coil 72 and therefore the current flowing from the generator through these two coils exerts a net armature-lifting or switch-closing effect and this same current flowing through series coils 70 and 76 causes a cumulative additional effect. Therefore switch 10 closes when the generator voltage is only slightly greater than that of the battery system.

As pointed out above, the closing of the switch shunts out the hold out coil 74 but at this time there is little or no current flowing through the holdout coil and therefore the shunting of this coil does not cause a material change in the magnetic balance of the system. Furthermore, the voltages of the generator and the battery system, being substantially equal when the switch is closed, there is no appreciable charging current flowing immediately after the closing of the switch and therefore the effects of the series coils 70 and 76 are not changed materially; and there is no substantial change in the generator voltage and therefore the effects of the lifting and

balancing coils are not changed materially. Thus, during normal operation the speed of the generator is increased gradually so that the generator voltage rises to and then slightly exceeds that of the battery system at which time switch 10 closes.

After switch 10 is closed a further increase in the generator voltage causes a battery-charging current to flow from the generator through the battery system. The switch is held closed until such time as the voltage of the battery system becomes greater than that of the generator, which condition may result from a rise in the battery voltage or a reduction in the generator voltage, and in such event switch 10 will be opened promptly. The switch is opened by the higher voltage of the battery system causing a reverse current flow through series coils 70 and 76; the effect of this reverse current in coil 70 is to weaken the effect of lifting coil 68 and the effect of this reverse current in coil 76 is to strengthen balancing coil 72. Therefore, armature 28 is pulled down because the strength of the lower or switch-opening magnetic circuit exceeds that of the upper or switch-closing magnetic circuit. At the time switch 10 is opened the holdout coil 74 becomes energized and its effect is to aid coil 72; therefore the switch is held open.

During operation, a very high degree of sensitivity is obtained by carefully controlling the balance between the two magnetic circuits. In this regard the degree of saturation of the magnetic paths at the critical instance of closing or opening the switch is quite important. Also of importance is the air gap in each magnetic circuit between the respective end of the armature and the adjacent end ring. In this embodiment the ends of armature 28 are tapered at an angle of 5 degrees so as to provide surfaces which are substantially frusto-conical. The accurate alignment of armature 28 maintains an even balance and a proper distribution of the magnetic flux during operation.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In an electrical system of the character described wherein a generator of variable voltage is adapted to be connected to charge a battery when the generator voltage is higher than the battery voltage, a switch-operating mechanism comprising, a pair of potential coils comprising a first potential coil which tends to close the switch and a second potential coil which tends to open the switch, said coils being connected at one side adjacent the switch and on the generator side of the switch and being connected at their other side to the other side of the generator, a pair of current coils connected in series and between the generator and the switch, and a third potential coil connected in parallel with the switch and adapted to carry a control current the value and sense of which depend upon the relative values of the generator voltage and the battery voltage, said current coils being positioned respectively adjacent said first and second potential coils and being adapted to augment the effect of said first potential coil and to decrease the effect of said second potential coil when cur-

rent is flowing from the generator through the battery and being adapted to produce the opposite effects when current is flowing from the battery through the generator.

2. In an electrical system of the character described wherein a generator of variable voltage is adapted to be connected to charge a battery when the generator voltage is higher than the battery voltage, a switch-operating mechanism comprising, a pair of potential coils comprising a first potential coil which tends to close the switch and a second potential coil which tends to open the switch, said coils being connected at one side adjacent the switch and on the generator side of the switch and being connected at their other side to the other side of the generator, a pair of current coils connected in series and between the generator and the switch, and a third potential coil connected in parallel with the switch and adapted to carry a control current the value and sense of which depends upon the relative values of the generator voltage and the battery voltage, said current coils being positioned respectively adjacent said first and second potential coils and being adapted to augment the effect of said first potential coil and to decrease the effect of said second potential coil when current is flowing from the generator through the battery and being adapted to produce the opposite effects when current is flowing from the battery through the generator, said first and second potential coils being connected in series and said first coil having substantially one per cent more turns than said second potential coil.

3. In an electrical system for controlling the connection between a generator and a storage battery in which the generator is connected across the storage battery with a switch in the circuit therebetween, the combination of a first potential coil, a second smaller potential coil, said potential coils being connected in series between one side of said generator and one side of said switch, said first potential coil being associated with said switch and constructed to exert a closing force on said switch, said second potential coil being associated with said switch and constructed to exert an open force on said switch, a current coil associated with said first potential coil and in the magnetic circuit thereof, a current coil associated with said second potential coil and in the magnetic circuit thereof, said current coils being substantially identical and connected in series between one side of the generator and one side of the switch, said potential coils bridging said generator, and a hold-out coil connected between said generator and said storage battery and bridging said switch, said hold-out coil being associated with said second potential coil and in the magnetic circuit thereof, said hold-out being constructed to oppose said second potential coil when the generator voltage is above the battery voltage and vice versa.

4. In an electrical system for controlling the connection between a generator and a storage battery in which the generator is connected across the storage battery with a switch in the circuit therebetween, the combination of a first potential coil, a second smaller potential coil adapted to exert substantially one per cent less magnetic force than said first potential coil, said potential coils being connected in series between one side of said generator and one side of said switch, said first potential coil being associated with said switch and constructed to exert a closing force on said switch, said second potential

coil being associated with said switch and constructed to exert an opening force on said switch, a current coil associated with said first potential coil and in the magnetic circuit thereof, a current coil associated with said second potential coil and in the magnetic circuit thereof, said current coils being substantially identical and connected in series between one side of the generator and one side of the switch, said potential coils bridging said generator, and a hold-out coil connected between said generator and said storage battery and bridging said switch, said hold-out coil being associated with said second potential coil and in the magnetic circuit thereof, said hold-out coil being constructed to oppose said second potential coil when the generator voltage is above the battery voltage and vice versa.

5. In an electrical system for controlling the connection between a generator and a storage battery in which the generator is connected across the storage battery with a switch in the circuit therebetween, the combination of an armature connected to said switch to open and close it, a first potential coil, a second smaller potential coil, said potential coils being connected in series between one side of said generator and one side of said switch, said first potential coil being associated with said armature and constructed when energized to move said armature in a direction to close said switch, said second potential coil being associated with said armature and constructed when energized to move said armature in a direction to open said switch, a current coil associated with said first potential coil and in the magnetic circuit thereof, a current coil associated with said second potential coil and in the magnetic circuit thereof, said current coils being substantially identical and connected in series between one side of the generator and one side of the switch, said potential coils bridging said generator, and a hold-out coil connected between said generator and said storage battery and bridging said switch, said hold-out coil being associated with said second potential coil and in the magnetic circuit thereof, said hold-out coil being constructed to oppose said second potential coil when the generator voltage is above the battery voltage and vice versa.
